UNITED STATES PATENT OFFICE.

ARCHIBALD J. TURNER, OF CHICAGO, ILLINOIS, ASSIGNOR TO WILSON-WESTERN SPORTING GOODS COMPANY, OF CHICAGO, ILLINOIS, A CORPORATION OF DELAWARE.

INFLATABLE BALL.

Application filed May 29, 1926. Serial No. 112,427.

My invention relates to inflatable balls, and is concerned with the provision of improved means for closing the bladder insertion opening of such a ball.

- 5 Certain types of inflatable balls, notably footballs, must or should be provided with an exposed lace or the like to afford a series of ridges on the exterior surface of the ball for engagement by the fingers of a player in 10 effecting a pass. Heretofore the bladder insertion openings of such balls have been closed, and the said ridges afforded, by a lace passing through a plurality of apertures in the margins of the bladder insertion opening 15 of the ball cover. However, such laces as heretofore employed have been subject to the very serious objection that they have caused the margins of the bladder insertion opening to creep longitudinally of such 20 opening and oppositely to each other, the result being a cover which is bumpy and unsightly at and adjacent to the bladder insertion opening. Moreover when the margins of the opening have crept relatively 25 to each other, as aforesaid, the portions of the lace crossing the line of the insertion opening on the outside of the cover have taken position oblique to the line of the insertion opening, instead of extending directly 30 across it at right angles as is desirable in order that the ball may be of good appearance and in order that the exposed portions of the lace may be most effective in facilitating hand passing of the ball.
- 35 It will be observed that the cause of this creeping of the edges of the slit relative to each other is due to the fact that when the rows of holes are aligned so that each hole is directly opposite another hole and the 40 lacing is put in place loosely in the usual manner, the exterior parts of the lacing will extend at right angles to the slit, and the interior portions of the lacing will extend diagonally relative to the slit and all 45 in the same direction. When such a lace is pulled up, the exterior portions exert force at right angles to the slit merely drawing the slit together, but the interior diagonal portions each exert resultant force upon the 50 edges of holes which are not directly opposite each other, but which are off set one hole. This diagonal force may be resolved into two forces, one at right angles to the slit and one parallel to the slit, with the result that the said interior diagonal portions
- not only draw the slit together, but tend to slide the portions of the cover composing the two walls of the slit in the direction of the slit until the rows of holes have reached such a position that the exterior 55 parts of the lace and the interior parts of the lace are both diagonal with equal angularity. This tendency of the lace to slide the edges of the slit is opposed by the tension placed upon other parts of the ball, as 60 such creeping or sliding tends to distort the ball from its normal shape. By my invention, the interior portions of the lacing do not consist of single diagonal tension members 65 tending to slide the walls of the slit relative to each other, but of diagonal tension members crossing each other exerting balanced forces on the walls of the slit in the direction of said slit and thereby maintaining the exterior portions of the lacing 70 parallel and at right angles to the slit without any bulging of the walls of the slit at either end. In accomplishing this result, it is necessary to double the upper members of the lacing at a plurality of points, but not 75 80 at all points, but I prefer to provide the exterior portions of the lacing with two plies of lacing at every point, thereby producing a uniform exterior surface.
- I have devised lacing means for closing 85 the bladder insertion opening of a football or the like, which has the following very desirable characteristics:
- (1) The lace when properly applied has no tendency to cause the margins of the insertion opening to creep relatively to each other.
- (2) The portions of the lace which lie outside of the cover are parallel to each other and at right angles to the abutting margins 95 of the bladder insertion opening.
- (3) The portions of the lace which lie outside of the cover are so disposed as to afford pronounced two-ply ridges which have been found very desirable and effective 100 from the standpoint of a player making a forward pass.
- The improvements herein described are admirably adapted for incorporation in a ball (such as disclosed in my co-pending 105 application, Serial No. 24,337, filed April 20, 1925,) which is capable of being inflated after the closure of the bladder insertion opening, but it should be understood that the improvements of the present invention 110

are not limited to footballs arranged to be so inflated.

In the accompanying drawings illustrating a preferred embodiment of my invention, 5 Fig. 1 is a top plan view of a football embodying the improvements of the present invention.

Fig. 2 is an enlarged fragmentary interior plan view of the parts of the ball with 10 which the present invention is particularly concerned,

Fig. 3 is an enlarged fragmentary sectional view taken on the line 3-3 of Fig. 2, and

15 Fig. 4 is a diagrammatic view illustrating in a general way the positions taken by the several portions of the lace when the same is properly applied to the ball cover, as hereinafter described.

20 Similar characters of reference refer to similar parts throughout the several views.

The football shown in the drawing comprises the usual cover consisting of a plurality (usually 4) leather sections 10-10 25 which have their contiguous margins stitched together in the usual or any suitable manner. For a short distance, approximately three or four inches, the contiguous margins of a pair of the cover members 30 are left unstitched to provide the bladder insertion opening 11. The bladder is not shown in the drawing, as my present invention is in no way concerned with the details thereof. It will be understood that 35 the bladder may be of the conventional type comprising a rubber inflating tube which is closed and tucked inside the cover after the bladder has been inflated, or may be a bladder of the more desirable type, shown in my 40 co-pending application aforesaid, which is adapted to be inflated after the bladder insertion opening of the cover has been closed.

Disposed inside the cover and stitched to the cover portions which lie on either side 45 of the slit or insertion opening 11 are reinforcing strips 12-12. The several lines of stitching whereby these reenforcing strips are secured to the cover are illustrated at 13, 14 and 15. It will be observed that the 50 proximal edges of the reenforcing strips lie flush with the edges of their respective cover members, so that when the margins of the slit 11 are brought into abutting relation the proximal edges of the reenforcing strips 55 will also lie in abutment, as illustrated in Fig. 3. Located alongside the slit or insertion opening 11 and extending through the reenforcing strips 12-12 and the cover members by which said strips are carried are 60 two rows of apertures a, b, c, d, etc., and a', b', c', d', etc., each aperture of each row being paired with and being located, relatively to the slit 11, directly opposite an aperture of the other row.

65 It will be understood by those skilled in

the art to which my invention relates that the cover may, if desired, be provided with the conventional fabric lining (not shown) and that, if desired, one or the other of the cover members adjacent the slit 11 may be 70 provided with the conventional flap (not shown) to lie between the bladder and the interior portions of the lace to prevent chafing of the bladder.

As thus far described, the ball shown in 75 the accompanying drawing need not differ essentially from balls in use prior to the advent of my present invention. I shall now describe the manner of applying the lace, which is the distinguishing feature of the 80 present invention.

The lace which I prefer to employ is of 85 strong, tough cowhide or rawhide and has considerable width as compared with its thickness.

In applying the lace, one of its ends is passed from the inside of the cover through one of the apertures a or a', say for instance aperture a', and is then extended across the slit 11 exteriorly of the cover and is 90 passed into the cover through aperture a. The same end of the lace is now extended across slit 11, interiorly of the cover and is again passed through apertures a' and a as before, the second exterior portion of the 95 lace passing between the apertures a and a' lying snugly upon and in registry with the first portion and with it constituting a sizable two-ply ridge at right angles to the slit 11. The lace is now adjusted in the apertures a and a' so that its ends are of substantially the same length. For convenience in description, the two substantially equally long ends of the lace will be designated as 100 X and XX.

The end X of the lace is now passed interiorly of the cover from aperture a' to aperture b and is passed through aperture b and then exteriorly of the cover to and through aperture b'. Similarly the end 110 XX of the lace is extended interiorly with the cover from aperture a to and through aperture b' and thence across slit 11 and through aperture b. It will be noted that the portion of lace end XX which extends exteriorly of the cover from aperture b to aperture b' lies snugly upon the portion of lace X which is similarly extended between such apertures.

The manner of lacing just described is 120 continued until each of the lace ends X and XX has been passed through all of the apertures. After this has been accomplished, the ends of the lace are passed upwardly through the right end (Figs. 1 and 125 2) of the slit 11 and are passed in edgewise contact with each other over the last one of the several exposed parallel two-ply lace sections, and then under the rest of said 130 exposed two-ply lace sections, as is clearly

illustrated in Fig. 1. All slack in the lace sections is now taken up, with the result that each of the exposed two-ply lace sections lies exactly parallel to the others and 5 at right angles to the line of the closed slit 11.

It will be observed that, while that portion of the lacing at the extreme left end of Figs. 1, 2 and 4 might have been made with 10 a single ply, for the sake of providing a uniform exterior surface, thereby permitting a better grip, I prefer to also double the exterior strand at this point.

It will be noted that each contiguous pair 15 of the exposed two-ply lace sections aforesaid may be regarded as constituting the sides of a rectangle having its angles in four of the cover apertures, and that the interior crossed over portions of the lace which pass 20 through said apertures are bisectors of the angles of such rectangle. As a result of this construction, the several exposed two-ply portions of the lace are held exactly parallel to each other and at right angles 25 to the line of the closed slit 11, and with the further result that the cover does not have any tendency to become bunched at or adjacent to the insertion opening.

While I prefer to hold or secure the 30 extremities of the lace by passing them under the parallel exposed two-ply portions of the lace, as aforesaid, it will be understood that I do not limit myself to this expedient.

What I claim is new and desire to secure 35 by Letters Patent of the United States is—

1. In an inflatable ball, a cover provided with a slit constituting a bladder insertion opening, a row of spaced apertures in each of the margins of said slit, each of said 40 apertures being paired with and located directly opposite an aperture of the other row, and a lace passing through said apertures and comprising a plurality of portions, each 45 consisting of two flat plies superposed, extending across said slit exteriorly of the cover, and a plurality of one-ply crossing

portions on the interior of the cover maintaining the parallelism of the exterior two-ply portions aforesaid.

2. In an inflatable ball, a cover provided 50 with a slit constituting a bladder insertion opening, a row of spaced apertures in each of the margins of said slit, each of said apertures being paired with an aperture of the other row, and a lace passing through 55 said apertures and comprising a plurality of two-ply portions extending across said slit exteriorly of the cover, and a plurality of one-ply portions each crossing another on the interior of the cover maintaining the 60 parallelism of the external two-ply portions aforesaid.

3. In an inflatable ball, a cover provided 65 with a slit constituting a bladder insertion opening, a row of spaced apertures adjacent each margin of said slit, each of said apertures being paired with and located directly opposite an aperture of the other row; and a lace passing through said apertures and comprising a plurality of portions, each 70 consisting of two contiguous parallel plies extending across said slit on one side of the cover, and a plurality of one-ply crossing portions on the other side of the cover maintaining the parallelism of the aforesaid two- 75 ply portions.

4. In an inflatable ball, a cover provided 80 with a slit constituting a bladder insertion opening having a row of lacing apertures on each side thereof, the apertures on opposite sides of the slit being arranged in pairs on lines substantially perpendicular to the slit; and a lace threaded through the apertures, in two-ply parallel portions extending 85 perpendicularly across the slit on one side of the cover and in one-ply crossing portions extending diagonally across the slit on the other side of the cover.

In witness whereof, I hereunto subscribe my name this 27th day of May, 1926.

ARCHIBALD J. TURNER.
